Specification for Design.

Patented Oct. 25, 1921.

Application filed February 10, 1921. Serial No. 444,041. Term of patent 3½ years.

To all whom it may concern:

Be it known that I, JESSE W. BETTMANN, muffler in position of use, and a citizen of the United States, residing in New York city, in the county of New York and State of New York, have invented a new, original, and ornamental Design for a Muffler, of which the following is a specification, reference being had to the accompanying drawing, forming a part thereof, wherein—

Figure 1 is a perspective front view of the Fig. 2 is a top view of the muffler in extended position, together with a plan view of the ring used in combination with the muffler.

What I claim is:

The ornamental design for a muffler, as shown.
